HOLDER FOR ARTICLES SUCH AS PENS AND PENCILS

Olaf A. Johnson, Minneapolis, Minn., assignor of one-third to Joseph P. O'Brien and one-third to A. Janda, both of Wahpeton, N. Dak.

Application July 17, 1942, Serial No. 451,296

22 Claims. (Cl. 120—108)

This invention has relation to a holder for articles such as pens and pencils, and has more particular relation to a so-called pen holder.

An object of the invention is to provide a holder for articles which will be of novel and improved construction.

A further object is to provide a holder for articles such as pens and pencils wherein will be incorporated various improved features and characteristics of construction which will be novel both as individual entities of the holder and in combination with each other.

A further object is to provide a holder for an article such as a pen or pencil which will include a case adapted to house the article, a holder or stand for said article carried by the case and removably supporting the article, and novel and improved mechanism through the instrumentality of which said article selectively can be enclosed by said case or accessible for use.

A further object is to provide a holder for an article such as a pen or pencil which will include a case for housing the article, a cover for the case, a holder proper or stand for said article carried by said case and removably supporting the article, and novel and improved mechanism adapted to be actuated selectively to cause said article to be housed by said case beneath its cover or to be accessible at position outside of said case.

And a further object is to provide a holder for articles such as pens and pencils which will include features and characteristics as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawing forming a part of this specification:

Fig. 1 is a top plan view of a holder for articles such as pens and pencils made according to the invention;

Fig. 2 is a side elevational view of the holder of Fig. 1 disclosing, in dotted lines, a pen as when housed by said holder, and, in full lines, as when accessible for use;

Fig. 3 is an enlarged fragmentary bottom plan view of the holder of Figs. 1 and 2, with the lower wall of the case of said holder removed;

Fig. 4 is a detail sectional view, taken on line 4—4 in Fig. 3; and

Fig. 5 is a detail sectional view, taken on line 5—5 in Fig. 3.

With respect to the drawing and the numerals of reference thereon, a rectangular case of the holder is denoted at 10. As disclosed the case 10 consists of an upper wall 11, a lower wall 12, opposite side walls 13, 13 and opposite end walls 14, 14. The upper and lower walls 11 and 12 are parallel and are spaced apart a distance considerably less than a measurement representing the distance apart of the opposite side walls 13, 13. The opposite end walls 14, 14 are spaced apart a distance greater than the measurement representing the distance between the opposite side walls 13, 13. As shown, the opposite side walls 13, 13 are parallel, as are also the opposite end walls 14, 14. The upper, lower, side and end walls of said case 10 are spaced apart to provide a compartment 15 within the case of sufficient size or capacity to nicely house an article, such, for example, as a pen 16, to be enclosed in said case.

The upper wall 11 of the case 10 is provided with a rectangular opening or slot 17, extending generally longitudinally, but obliquely, of said upper wall 11, of length greater than that of the article or pen 16 and of width to permit free passage of said article or pen through said rectangular opening or slot.

Desirably, the lower or outer surface of the lower wall 12 of said case 10 may be provided with pieces of felt 18 adapted to rest upon a supporting surface, such as a desk, for the case, preferably to cause the upper and lower walls 11 and 12 of said case to be disposed horizontally.

A cover for the rectangular opening or slot 17 through the upper wall 11 of the case 10 is designated at 19, and a hinge or pivotal support for said cover 19 is represented at 20. More explicitly, an ear 21, rigid with the inner surface of the upper wall 11 and situated at a side of the rectangular opening or slot 17, fixedly supports a pin 22 disposed parallelly of said rectangular opening or slot. A bracket member 23 includes an end portion 24 thereof rigid with the inner or under surface of the cover 19, an intermediate curved portion 25 thereof which extends from said end portion 24 and passes freely through the rectangular opening or slot 17 into the compartment 15 of the case 10, an annular portion

26 thereof mounted upon said pin 22, a straight connecting portion 27 thereof between said annular portion and the end of the intermediate curved portion 25 spaced from said end portion 24, and a straight end portion 28 thereof at a side of the annular portion 26 spaced from the straight connecting portion 27. The straight connecting portion 27, the straight end portion 28 and the annular portion 26 of the bracket member 23 constitute the inner end portion of said bracket member mounted upon the pin 22 so that said straight connecting portion is substantially perpendicular to the upper wall 11 of the case 10 and extends downwardly therefrom, and so that the straight end portion 28 is substantially parallel with and in spaced relation to said upper wall 11. The portions 27 and 28 of the bracket member 23 are as shown at right-angle relation to each other.

The cover 19 is adapted normally to rest, by reason of its weight, or gravity, upon the upper surface of the upper wall 11 of the case 10, in closing relation to the rectangular opening or slot 17, and devices are provided through the instrumentality of which said cover can be swung to open and closed positions to allow passage of the article or pen 16 through said rectangular opening or slot 17. Of said mentioned devices, 29 is a lever, within the compartment 15, having an intermediate portion thereof pivoted at 30 upon the upper wall 11 of the case 10 and an end portion 31 thereof situated adjacent and between the portions 27 and 28 of the bracket member 23 for selective engagement with each of these mentioned portions. An end portion 32 of the lever 29 opposite the end portion 31 includes an arcuate slot 33 disposed generally longitudinally of said lever 29. A shaft 34, within the compartment 15 and disposed perpendicularly of the lever 29 and the rectangular opening or slot 17, adjacent an end of said opening or slot, is rotatably mounted in spaced apart supporting brackets 35, 35 upon the inner surface of the upper wall 11 of the case 10. Said shaft 34 includes a crank 36 disposed at angular relation to the shaft and situated in the arcuate slot 33. The construction and arrangement are such that when the crank 36 is at either end of the arcuate slot 33, the cover will be in closed position by reason of its weight, or gravity, and also such that movement of said crank from either end of said arcuate slot to the midlength thereof will cause the cover 19 to be forced or thrown to open position, by reason of engagement of the end portion 31 with the portion 27 of the bracket member 23, and that movement of the crank from the midlength of the arcuate slot to either end thereof will cause said cover 19 to become closed, by reason of engagement of said end portion 31 with the portion 28 of said bracket member 23.

A holder proper or stand for the article or pen 16 is represented at 37. As shown, said holder proper or stand includes a tubular portion 38 thereof into which the article or pen is removably, frictionally fitted, and a retaining portion 39 thereof rotatably supported upon the shaft 34 and movable in a rectangular slot 40 in the upper wall 11 of the case 10. An actuator 41 for the holder proper or stand 37 is fixed upon the shaft 34, and the retaining portion 39 of said holder proper or stand is situated between said actuator 41 and the adjacent supporting bracket 35, thus to be held against movement longitudinally of said shaft 34. That is, the holder proper or stand 37, while rotatable upon the shaft

34, is fixed against movement therealong. The actuator 41 includes an annular surface 42 at the lower side thereof concentric with the shaft 34, and a radial shoulder or stop, denoted 43 and 44, respectively, at each end of said annular surface. An actuating pin 45 upon a side surface of the retaining portion 39 of the holder proper or stand 37, at the side of the shaft 34 opposite the tubular portion 38 is adapted to travel adjacent said annular surface 42 and to come into engagement with one or the other of the shoulders or stops 43 or 44, as the case may be, with rotation of said shaft 34 and the actuator 41 fixed thereon. That is, the construction and arrangement are such that the shaft 34 can have free turning movement relative to the holder proper or stand 37 while the actuating pin 45 lies between the shoulders or stops 43 and 44, and that movement of rotation of said shaft can be imparted to said holder proper or stand through the instrumentality of engagement between said actuating pin and a shoulder or stop 43 or 44 of the actuator 41, as will be understood.

The shaft 34 fixedly carries a gear 46, and a rack 47 which meshes with said gear 46 is mounted, as at 48, to be slidably in an opening through the upper wall 11 of the case 10. Also, said shaft 34 fixedly carries a gear 49, and a rack 50 which meshes with said gear 49 is mounted, as at 51, to be slidably in a different opening through said upper wall 11. The racks 47 and 50 as disclosed are perpendicular to the upper and lower walls of the case and are movable in direction toward and away from the lower wall of said case, longitudinally of said racks. Enlarged heads of the racks 47 and 50, above and in spaced relation to the upper wall 11 of the case, are designated 52 and 53, respectively. As will be apparent from Fig. 3 of the drawing, the racks 47 and 50 are disposed at opposite sides of the shaft 34. That is, the rack 47 engages the gear 46 at the left side of the shaft 34 and the rack 50 engages the gear 49 at the right side of said shaft in said Fig. 3.

Supposing the article or pen 16 to be enclosed by the case 10 and the cover 19 to be in closed position, as in Figs. 1 and 3, said article or pen will be moved to accessible position, outside of the case, as in Fig. 2, in response to depression 50 of the rack 50 caused by pushing downwardly upon the enlarged head 53. With downward pushing of said rack 50, the gear 49 will be caused to rotate in direction to cause the crank 36 to be moved from its position as in Fig. 3 to the opposite end of the arcuate slot 33. During the movement of the crank 36 from its position as in said Fig. 3 to the midlength of the arcuate slot 33, the cover 19 will be moved to open position, by reason of engagement of the end portion 31 of the lever 29 with the portion 27 of the bracket member 23, and during the movement of said crank 36 from the midlength of said arcuate slot to the end of the slot opposite the end at which the crank is shown in Fig. 3, said cover 19 will be caused to move to closed position, by reason of engagement of said end portion 31 of said lever 29 with the portion 28 of said bracket member 23. That is, with movement of the crank 36 from the midlength to either end of the arcuate slot 33 the lever end portion 31 will engage the portion 28 of the bracket member 23 to cause the cover 19 to be overbalanced toward closing direction so that gravity will cause said cover member to move to closed position over the rectangular opening

or slot 17, and with movement of said crank 36 from either end to the midlength of said arcuate slot said lever end portion 31 will engage the portion 27 of said bracket member 28 to cause said cover 19 to be open. In Fig. 4, the shoulder or stop 44 is disclosed as adjacent the actuating pin 45, and this may be the arrangement when the holder proper or stand is in the case, as in Figs. 1 and 3. Upon depression of the rack 50, the actuator 41 will, evidently, be rotated in direction to cause said shoulder or stop 44 to be moved away from said actuating pin 45 and the shoulder or stop 43 to be moved toward and against said pin. The construction and arrangement are such that, with depression of the rack 50, the shoulder or stop 43 will engage the actuating pin 45 at the interval when the crank 36 is approaching the midlength of the arcuate slot 33 to cause the cover 19 to be wide open. Obviously, the holder proper or stand will remain stationary within the case 10 until said shoulder or stop 43 becomes engaged against said actuating pin 45. Upon further depression of the rack 50, after the shoulder or stop 43 has engaged the actuating pin 45, said holder or stand will be rotated from the position as in Fig. 3 to the position as in Fig. 2. The construction and arrangement are such that the article or pen 16 will be swung upwardly past the rectangular opening or slot 17, while the cover 19 is in open position, when said crank 36 is approaching the midlength of said arcuate slot 33 from the end in which shown in said Fig. 3 and is receding from said midlength of the slot toward the end thereof opposite that at which the crank is shown in Fig. 3, and that said cover 19 will be caused to move to closed position, back of the article or pen, as soon as said article or pen has moved to position clear of said cover. Stated differently, the article or pen is adapted to be moved to its accessible position, outside of the case 10, while the cover 19 is clear of the rectangular opening or slot 17, and said cover is adapted to be moved to closed condition after said article or pen has been lifted out of said case. Clearly, the article or pen will remain at position to which moved outside of the case, by reason of the engagement between the gear 49 and the rack 50 and between the shoulder or stop 43 and the actuating pin 45. Supposing the article or pen to be outside of the case and the cover 19 to be in closed position, as in Fig. 2, said article or pen will be moved to position where enclosed by said case, as in Figs. 1 and 3, in response to depression of the rack 47 caused by pushing downwardly upon the enlarged head 52. With downward pushing of said rack 47, the gear 46 will be caused to rotate in direction to cause the crank 36 to be moved from the end of the arcuate slot 33 opposite that in which shown in Fig. 3 to the end in which said crank is shown in said Fig. 3. During such movement of the crank the cover 19 will be moved to open position and then to closed position, in the manner as before set forth, and the shoulder or stop 43 will be moved in direction away from and the shoulder or stop 44 will approach the actuating pin 45. The holder proper or stand 37 when in accessible position is at somewhat spaced relation to the adjacent end of the cover 19, overbalanced against the end wall 54 of the slot 40, as in Fig. 2. Said end wall 54 serves as a stop for said holder proper or stand. When the holder proper or stand drops against the end wall 54 the actuating

pin 45 becomes slightly spaced from the shoulder or stop 43, as will be evident. With movement of the rack 47 downwardly, the shoulder or stop 44 picks up the pin 45 to commence actuation of the holder or stand at the interval when the crank 36 is approaching the midlength of the arcuate slot 33, and said holder or stand is released to gravity while said crank is at and receding from the midlength of said arcuate slot, so that the article or pen is allowed to drop downwardly past the rectangular opening or slot 17 while the cover 19 is in open position. That is, the article or pen is deposited into the case during the interval the crank 36 is approaching the midlength of the arcuate slot 33 and is receding from the midlength of said slot, toward the position as in Fig. 3. Evidently, the cover 19 will be caused to move to closed position, over the article or pen, as soon as said article or pen has moved to position within the case clear of said cover. Stated differently, the article or pen is adapted to be moved to its enclosed position within the case while the cover is clear of the rectangular opening or slot 17, and said cover is adapted to be moved to closed condition after said article or pen has been deposited within said case. Evidently, the rack 50 is caused to be elevated when the rack 47 is depressed, and vice versa.

30 3. What is claimed is:

1. A holder for an article such as a pen or pencil, comprising a case including a compartment for housing said article, a stand for removably supporting the article upon the case, and means for causing said stand to be actuated selectively to situate said article within said compartment and at accessible position outside of said case.

2. A holder for an article such as a pen or pencil, comprising a case adapted to house said article, a holder proper for the article carried by said case and removably supporting said article, and means through the instrumentality of which said article selectively can be either enclosed by said case or accessible for use.

3. A holder for an article such as a pen or pencil, comprising a case for housing said article, a cover for said case, a stand for the article carried by the case and removably supporting said article, and means adapted to be actuated selectively to cause said article to be either housed by the case beneath said cover or accessible at position outside of said case.

4. A holder for an article such as a pen or pencil, comprising a case including a compartment for housing said article, a holder proper for removably supporting the article upon said case, means for causing said holder proper to be situated to position said article within said compartment, and means for causing the holder proper to be situated to position the article at location outside of said case.

5. A holder for an article such as a pen or pencil, comprising a case including a compartment for housing said article, a cover for said compartment, a holder proper for removably supporting the article upon said case, and means for causing said holder proper to be actuated selectively to cause said article to be housed within said compartment beneath said cover and at accessible position outside of said case.

6. A holder for an article such as a pen or pencil, comprising a case including a compartment

ment for housing said article, a cover for said compartment, a holder proper for removably supporting the article upon said case, means adapted to be actuated to cause said holder proper to be situated to position said article within said compartment beneath said cover, and means adapted to be actuated to cause the holder proper to be situated to position the article at location above said case.

7. A holder for an article such as a pen or pencil, comprising a case adapted to house said article, a holder proper for the article carried by said case and removably supporting said article, means for actuating said holder proper to position causing said article to be enclosed by said case, and means for actuating the holder proper to position causing the article to be accessible outside of said case.

8. A holder for an article such as a pen or pencil, comprising a case for housing said article, a cover for said case, a stand for the article carried by the case and removably supporting said article, means for actuating said stand to position causing said article to be enclosed by said case beneath said cover, and means for actuating the stand to position causing the article to be accessible outside of said case.

9. A holder for an article such as a pen or pencil, comprising a case for housing said article, a cover for said case, a stand for the article carried by the case and removably supporting said article, and mechanism adapted to be actuated selectively to cause said article to be either housed by the case beneath said cover or accessible at location outside of said case, said mechanism including means for causing said cover normally to be in closed position upon the case and to be removed from said case concurrently with removal of the article from and deposit of said article within the case.

10. A holder for an article such as a pen or pencil, comprising a case for housing said article, a cover for said case, a stand for the article carried by the case and removably supporting said article, mechanism adapted to be actuated to cause said article to be housed by the case beneath said cover, mechanism adapted to be actuated to cause the article to be accessible at location outside of said case, and means for causing said cover normally to be in closed position upon said case and to be removed from the case concurrently with removal of the article from and deposit of said article into the case.

11. A holder for an article such as a pen or pencil, comprising a case including a compartment for housing said article and having an opening to said compartment, a cover for said compartment normally closing said opening, a stand for removably supporting the article upon said case, and mechanism for causing said stand to be actuated selectively to cause said article to be moved inwardly through said opening into said compartment and to be moved outwardly through said opening to position outside of said case, said mechanism including means for causing said cover to be removed from the opening concurrently with removal of the article from and deposit of the article within the case by way of said opening.

12. A holder for an article such as a pen or pencil, comprising a case including a compartment for housing said article and having an opening to said compartment, a cover for said compartment normally closing said opening, a stand for removably supporting the article upon

5 said case, mechanism for causing said stand to be actuated to cause said article to be moved inwardly of said case through said opening into said compartment and to be moved outwardly through said opening to position outside of said case, and means for causing said cover to be removed from the opening concurrently with passage of the article through said opening.

13. A holder for an article such as a pen or pencil, comprising a case including a compartment for housing said article and having an opening to said compartment, a cover for said compartment normally closing said opening, a stand for removably supporting the article upon said case, mechanism for causing said stand to be actuated to cause said article to be moved inwardly of said case through said opening into said compartment, mechanism for causing the stand to be actuated to cause the article to be moved outwardly through said opening to position outside of said case, and means for causing said cover to be removed from the opening concurrently with passage of the article through said opening.

14. A holder for an article such as a pen or pencil, comprising a case including a compartment for housing said article and having an opening to said compartment, a cover for said compartment normally closing said opening, a shaft rotatably mounted within said compartment, a stand pivotally mounted upon said shaft for removably supporting the article, and mechanism for causing said stand to be actuated selectively to cause said article to be moved inwardly through said opening into said compartment and to be moved outwardly through said opening to position outside of said case, said mechanism including means for causing said cover to be removed from the opening concurrently with removal of the article from and deposit of said article within the case.

15. A holder for an article such as a pen or pencil, comprising a case including a compartment for housing said article and having an opening to said compartment, a cover for said compartment normally closing said opening, a shaft rotatably mounted within said compartment, a stand pivotally mounted upon said shaft for removably supporting the article, mechanism for causing said stand to be actuated to cause said article to be moved inwardly of said case through said opening into said compartment and to be moved outwardly through said opening to position outside of said case, and means for causing said cover to be removed from the opening concurrently with passage of the article through said opening.

16. A holder for an article such as a pen or pencil, comprising a case including a compartment for housing said article and having an opening to said compartment, a cover for said compartment normally closing said opening, a shaft rotatably mounted within said compartment, a stand pivotally mounted upon said shaft for removably supporting the article, mechanism for causing said stand to be actuated to cause said article to be moved inwardly of said case through said opening into said compartment, mechanism for causing said stand to be actuated to cause the article to be moved outwardly through said opening to position outside of said case, and means for causing said cover to be removed from the opening concurrently with passage of the article through said opening.

17. A holder for an article such as a pen or

pencil, comprising a case including a compartment for housing said article and having an opening to said compartment, a cover for said compartment normally closing said opening, a shaft rotatably mounted upon said case and situated within said compartment, a stand pivotally mounted upon said shaft for removably supporting the article, and mechanism including a rack and gear for causing said stand to be actuated selectively to cause said article to be moved inwardly through said opening into said compartment and to be moved outwardly through said opening to position outside of said case, said mechanism including means for causing said cover to be removed from the opening concurrently with removal of the article from and deposit of said article within the case.

18. A holder for an article such as a pen or pencil, comprising a case including a compartment for housing said article and having an opening to said compartment, a cover for said compartment normally closing said opening, a shaft rotatably mounted upon said case and situated within said compartment, a stand pivotally mounted upon said shaft for removably supporting the article, mechanism including a rack and gear for causing said stand to be actuated to cause said article to be moved inwardly of said case through said opening into said compartment and to be moved outwardly through said opening to position outside of said case, and means for causing said cover to be removed from the opening concurrently with passage of the article through said opening.

19. A holder for an article such as a pen or pencil, comprising a case including a compartment for housing said article and having an opening to said compartment, a cover for said compartment normally closing said opening, a shaft rotatably mounted upon said case and situated within said compartment, a stand pivotally mounted upon said shaft for removably supporting the article, mechanism including a rack and gear for causing said stand to be actuated to cause said article to be moved inwardly of said case through said opening into said compartment,

5 mechanism including a rack and gear for causing said stand to be actuated to cause the article to be moved outwardly through said opening to position outside of said case, and means for causing said cover to be removed from the opening concurrently with passage of the article through said opening.

10 20. The combination as specified in claim 17, wherein said mechanism includes a lost motion connection between said shaft and said stand.

15 21. A holder for an article such as a pen or pencil, comprising a case including a compartment for housing said article and having an opening to said compartment, a cover for said compartment normally closing said opening, a stand for removably supporting the article upon said case, manually operable mechanism for causing said stand to be actuated to cause said article to be moved inwardly of said case through said opening into said compartment and to be moved outwardly through said opening to position outside of said case, and means operative in response to actuation of said mechanism for causing said cover to be removed from the opening concurrently with passage of the article through said opening.

25 22. A holder for an article such as a pen or pencil, comprising a case including a compartment for housing said article and having an opening to said compartment, a cover for said compartment normally closing said opening, a stand for removably supporting the article upon said case, manually operable mechanism for causing said stand to be actuated to cause said article to be moved inwardly of said case through said opening into said compartment, manually operable mechanism for causing the stand to be actuated to cause the article to be moved outwardly through said opening to position outside of said case, and means operative in response to actuation of each of said mechanisms for causing said cover to be moved from the opening concurrently with passage of the article through said opening.

OLAF A. JOHNSON.
